INK FEED

Henry A. Wise Wood, New York, N. Y., assignor to
Wood Newspaper Machinery Corporation, New
York, N. Y., a corporation of Virginia

Application November 5, 1928, Serial No. 317,417
Renewed May 24, 1934

14 Claims. (Cl. 101—363)

This invention relates to a device for feeding ink from the fountain roll to the ink distributing part of a printing press or the like.

The principal objects of the invention are to provide a construction by which any variation in the distance of the fountain roll from the pick-up roll, or other roll to which it delivers, will not affect the thickness of the ink film delivered, thus providing a uniform flow of ink; to provide means whereby it will not be necessary to keep the fountain roll and pick-up roll accurately adjusted as to each other, or even to have them rotate in opposite directions, as is usual, at their points of surface contact, and to provide means whereby practically all the ink on the surface of the fountain roll will be transferred to the pick-up roll at all times and without change in the thickness thereof, even if the fountain roll vibrates or there is a variable amount of ink in the fountain.

Other objects and advantages of the invention will appear hereinafter.

Reference is to be had to the accompanying drawings in which:

Fig. 1 is an end view partly in section of an ink distributing mechanism showing a preferred embodiment of this invention, and

Fig. 2 is a side elevation.

Although capable of application to other types of inking apparatus it is shown as applied to one in which the fountain roll 10 supplies ink to the pick-up roll 11 which, by means of transfer rolls 12, delivers it to the ink drum 13. The fountain roll is located in a fountain 14 as usual and is provided with an ink adjusting blade 15 adjusted by screws 16, as is customary.

For obtaining the above mentioned results I provide means, mounted rigidly with respect to the pick-up roll, for constantly engaging the fountain roll, in spite of any vibration thereof, and guiding a uniform film of ink to the pick-up roll. So as to be rigidly mounted with respect to the pick-up roll, I locate a pair of suitable brackets 20 on the bearings 18 of the pick-up

roll. In these brackets are a pair of eccentric bushings 19 which can be turned to adjust their centers toward or from the pick-up roll to control the thickness of the ink film left on the pick-up roll. In these bushings are mounted journals 21 which support a deflecting knife 22. This knife is pivoted on these journals and they constitute its entire support.

It will be seen that by turning the bushings the deflecting knife 22 can be moved toward or from the pick-up roll 11 and it has only a small

possibility of movement because the edge 23 of this knife projects between the two rolls 10 and 11, which are spaced only slightly apart. The upper surface of the deflecting knife 22 is concave practically on the same radius as the roll 11 and its surface 24, about a quarter way around its journals, is concentric with the bearings. As the edge turns toward or from the pick-up roll, the rear part of it along the surface 24 will not change its distance from that roll. This distance is adjusted as stated above by turning the eccentric bushings and after adjustment it remains constant. The thickness of ink is determined by the blade 15, and the knife 22 merely removes all of it from the roller 10 and permits it to be drawn away by the pick-up roll 11.

A spring 25 is connected with the knife 22 and with a stationary pin 26 on the frame and constantly tends to pull the knife down toward the fountain roll.

In operation, it is obvious that with the rolls turning in the directions indicated, the ink on the fountain roll, after being spread out thin by the adjusting blade 15, must all be transferred on the top surface of the knife 22. This ink is then picked up by the pick-up roll and the thickness of the film thereon will be adjusted by the knife 15. The pick-up roll 11 can be rotated in either direction and the two rolls can be rotated in opposite directions or in the same direction, as desired, with this mechanism because the ink is not transferred directly from one to the other.

In the old construction the pick-up roll is rigidly mounted but the fountain roll is pivotally mounted for adjustment and is also spring-supported. This mounting is sometimes detrimental to the close adjustment required between the two rollers in the old arrangement. The vibration incident to the machine and the variability of the level of the ink in the fountain roll has somewhat affected the space between the rollers and this has prevented the keeping of the two rollers, at every instant, at the same distance from each other.

With this deflector knife, the knife edge being held against the fountain roll, preferably, it scrapes the surface of the fountain roll and feeds the ink into contact with the pick-up roll through the concave space above the knife. After adjustment this space is constant and cannot be affected by any change in the position of the fountain roll, which may be moved up and down a short distance without affecting the delivery of the ink or the thickness of the film which it transfers to the pick-up roll.

It is to be noted that the deflector knife is mounted on bearings rigidly mounted with respect to the pick-up roll so that, if that is permitted to move, the deflector blade will have to move with it. Thus no vibration of either roll will affect the continuity of the ink film or its uniformity of thickness.

Although I have illustrated and described only one form of the invention I am aware of the fact that modifications can be made therein by any person skilled in the art without departing from the scope of the invention as expressed in the claims. Therefore, I do not wish to be limited in this respect but what I do claim is:—

15. 1. In an inking device, the combination with a fountain roll and pick-up roll, of means adjacent said rolls for guiding the ink from the fountain roll to the pick-up roll independently of variations in the positions of the fountain roll:

20. 2. In an ink distributing mechanism, the combination with a fountain roll and pick-up roll spaced apart, of a knife constantly bearing on the fountain roll, irrespective of variations in the position thereof, and having a surface for guiding the ink into a position to be picked up by the surface of the pick-up roll.

30. 3. In an ink distributing mechanism, the combination with a fountain roll and a pick-up roll spaced apart, of a deflector having an edge located between said rolls and bearing constantly on the fountain roll and having a concave surface extending from said edge to a position more closely adjacent to the pick-up roll for receiving the ink and guiding it to a position to be taken up by the latter.

35. 4. In an ink distributing mechanism, the combination with a fountain roll and a pick-up roll, of a deflector having an edge extending along the fountain roll, and yielding means for constantly holding said edge in contact with said fountain roll, said deflector having a surface for receiving the ink taken off the fountain roll and close enough to the pick-up roll to apply it thereto.

40. 5. In an ink distributing mechanism, the combination with a fountain roll and pick-up roll spaced apart, of a knife constantly bearing on the fountain roll, and having a surface for guiding the ink into a position to be picked up by the surface of the pick-up roll, said knife being movable about an axis and having a rear surface concentric with said axis whereby such movement will not affect the distance of the rear surface from the pick-up roll.

45. 6. In an ink distributing mechanism, the combination with a fountain roll and a pick-up roll spaced apart, of a knife constantly bearing on the fountain roll and having a surface for guiding the ink into a position to be picked up by the surface of the pick-up roll, and eccentric bearings in

50. which said knife is mounted, adapted to be ad-

justed to control the distance of the knife from the pick-up roll and keep that distance constant during operation.

5. 7. In an inking device, the combination with a fountain roll and pick-up roll, of means adjacent said rolls rigidly mounted with respect to said pick-up roll for transferring the ink from the fountain roll to the pick-up roll independently of variations in the position of the fountain roll.

10. 8. In an ink distributing mechanism, the combination with a fountain roll and a pick-up roll spaced slightly apart, of means adjacent said rolls rigidly mounted with respect to said pick-up roll projecting between the rolls for engaging the fountain roll, and picking up ink therefrom and 15 guiding it into a position to be taken up by the pick-up roll and yielding means for holding the first named means in close contact with the fountain roll.

20. 9. In an ink distributing mechanism, the combination with a fountain roll and a pick-up roll spaced slightly apart, of means projecting between them for engaging the fountain roll and picking up ink therefrom and guiding it into a position to be taken up by the pick-up roll, said 25 means constantly bearing on the fountain roll irrespective of variations in the position thereof.

30. 10. In an ink distributing mechanism, the combination with a fountain roll and a pick-up roll spaced slightly apart, of means adjacent said 30 rolls rigidly mounted with respect to said pick-up roll projecting between the rolls for engaging the fountain roll and picking up ink therefrom and guiding it into a position to be taken up by the pick-up roll, said means constantly bearing on 35 the fountain roll irrespective of variations in the position thereof.

40. 11. An inking mechanism including in combination a fountain roller, an ink drum positioned above said roller and stationary means for transferring ink from the roller to said drum.

45. 12. An inking mechanism including in combination a fountain roller, an ink drum directly above said roller, and means for removing a continuous film of ink from said roller and transferring it to said drum.

50. 13. An inking mechanism including in combination a fountain roller, an ink drum directly above and adjacent to said roller and means for removing all the ink from the roller and transferring it to the drum.

55. 14. An inking mechanism including in combination a fountain roller, an ink drum closely adjacent to said roller and positioned directly above said roller, and a blade positioned between said roller and drum at the point where said roller and drum are closest to each other for transferring ink to said drum.

60. HENRY A. WISE WOOD. 60
